UNITED STATES PATENT OFFICE.

FREDERICK G. FRANKENBERG, OF ST. LOUIS, MISSOURI, ASSIGNOR OF
TWO-THIRDS TO MARY C. METCALFE, OF SAME PLACE.

DESIGN FOR A VAPOR-LAMP.

SPECIFICATION forming part of Design No. 30,904, dated May 30, 1899.

Application filed March 24, 1899. Serial No. 710,382. Term of patent 3½ years.

To all whom it may concern:

Be it known that I, FREDERICK G. FRANKENBERG, a citizen of the United States, residing in the city of St. Louis, State of Missouri, 5 have invented and produced a new and original Design for Vapor-Lamps, of which the following is a specification.

The figure is a side elevation of a vapor-lamp embodying my new design.

10 As shown in the drawing, the leading or essential features of my new design consist of the base 1; the post 2, extending upwardly from the base; the cylindrical portion 3 upon the post 2, intermediate of its ends; the portion 4, extending horizontally from the portion 3; the valve-casing 5, extending from the portion 4; the curved portion 6, extending from the valve-casing; the tank 7 upon

the upper end of the portion 6; the portion 8, extending from the portion 3 in the direction opposite to the portion 4; the elbow 9, extending downwardly from the portion 8; the portion 10, extending downwardly from the elbow; the union 11, extending downwardly from the portion 10; the U-shaped 25 portion 12, extending laterally from the union 11, and the curved portion 13, extending downwardly from the union 11.

I claim—

20 The design for a vapor-lamp, substantially 30 as herein shown and described.

FREDERICK G. FRANKENBERG.
